ELECTRIC TOOTHBRUSH UNIT OR THE LIKE

Melvin H. Boldt, Glenview, Ill., assignor to National
Presto Industries, Inc., Eau Claire, Wis., a corporation
of Wisconsin

Filed Mar. 13, 1964, Ser. No. 78,985

Term of patent 14 years

(Cl. D4—3)

FIG. 1

FIG. 2

FIG. 5

FIG. 4

FIG. 3

FIGURE 1 is a front elevational view of an electric toothbrush unit or the like showing my new design;

FIGURE 2 is a side elevational view thereof, the opposite side being a mirror image thereof;

FIGURE 3 is a rear elevational view thereof;

FIGURE 4 is a top plan view thereof; and

FIGURE 5 is a bottom plan view thereof.

The dominant features of my design for an electric toothbrush unit or the like reside in the portions shown in full lines.

I claim:

The ornamental design for an electric toothbrush unit or the like, substantially as shown and described.
